Primary Examiner — Dominic Simone(74) Attorney, Agent, or Firm — Banner & Witcoff, Ltd.(57) CLAIM

The ornamental design for a shoe outsole, as shown and described.

DESCRIPTION

FIG. 1 is a front perspective view of a shoe outsole showing my new design;

FIG. 2 is a plan view thereof; and,

FIG. 3 is a rear perspective view thereof.

The even length broken lines immediately adjacent to the shaded area represent unclaimed boundaries of the design. The even length broken lines illustrating joining ribs are for environmental purposes only and form no part of the claimed design. The uneven length broken lines showing the remainder of the shoe are for environmental purposes only and form no part of the claimed design.
